UNITED STATES PATENT OFFICE.

HERSCHEL E. TOWER, OF CINCINNATI, OHIO, ASSIGNOR TO THE BALDWIN COMPANY, OF CINCINNATI, OHIO.

CONTROL SWITCH.

Application filed November 18, 1927. Serial No. 234,149.

This invention relates to improvements in mechanical musical instruments and particularly to the control of the air tension.

At certain times it is desired to play rolls of music that are not designed to control the air tension automatically. When a roll without controls is played it is desirable to be able to control the tension of the air to any degree. One means of doing this is to open 10 certain holes in a switch, which causes the operation of the control pneumatics in the air tension box so that the pneumatic player action will operate at the desired tension.

The object of this invention is to have the 15 lever and valve on the control switch thrown to a position where the air tension in the player action will be controlled to the lowest degree after each roll is played. By this arrangement it is impossible for any one to put 20 a roll on and set the switch to the highest degree and let the player operate indefinitely as the lever will return automatically to the lowest mark when the player rewinds.

In the drawing, Fig. 1 is a diagrammatic 25 view of parts of a mechanical instrument, showing the roll box, gearing, control switch, pneumatic action, tension control box and power plant. Fig. 2 is a detailed view of the 30 control switch showing the tension control handle in two different positions and how it will be brought back to the lowest degree by the action of the rewind lever.

Fig. 3 is a perspective view of the control 35 switch set with two holes open and controlling the air tension to the medium or MF degree.

Fig. 4 is a perspective view of the control 40 switch in the position it will be returned to by the action of the rewind-replay lever and controlling or setting the air tension back to the lowest degree.

Referring more particularly to the drawings, the roll box 1 is made with a control switch 2, an indicator plate 3 and the lever 45 4 which being attached to the valve 5, can be moved to open one or more holes in the control switch 2, which holes are attached by suitable tubing to the air tension control box 6 so as to give the desired tension when playing 50 a roll of music that has no automatic expression holes cut in it.

The rewind and replay handle 7 that shifts 55 the pinion 8 and large gear 16, out of engagement with pin 17 and sprocket 18 for rewinding, and into engagement with clutch

collar 19 for playing has an extension 9 that extends below the shelf 10. A wire 11 is slidably mounted in a stud 12 on the lever 4 and pivotally attached at its other end to the extension 9 that extends below the shelf 10. 60 When the lever 4 is set at PP this wire will slide in the stud 12 and not move the lever 4.

When a roll has been put into the roll box 1 the rewind and replay handle 7 is slid to the left and the control lever 4 is moved to 65 either P, MF, F or FF position as desired. For instance, if the lever 4 is placed at MF position, then the valve 5 is moved far enough to open holes in the switch and operate respective valves in the tension control box 6 70 to give a medium tension of air.

Without the application of this invention, if the lever 4 were to be set at FF and the 75 player action set to rewind automatically and repeat and is then left to keep on playing, it would be such a strain on the pumper 13 and motor 14 that they would soon become overheated. To overcome this the wire 11 has a collar 15 that works against the stud 12 when the rewind handle is set to rewind, 80 forcing the lever 4 and the valve 5 to a position where all holes in the switch 2 are closed, thereby setting the air tension at the lowest degree for the start of the next roll. This also sets the air tension at the proper degree 85 to operate with a roll that has holes cut for the automatic control of the air tension.

Many different designs of switches may be used, but what I claim as my invention is:

1. A mechanical musical instrument having 90 air tension controlling means and gear shifting means and a connection from said gear shifting means to said air controlling means to set the said air controlling means at the lowest degree of tension after playing 95 each roll.

2. A mechanical musical instrument having 100 an air tension controlling switch with a stationary base, a movable part and a lever for controlling the position of the movable part, gearing for playing and rewinding a music roll, a rewind and replay handle for shifting the gearing to rewind and playing position, and a positive connection from the 105 rewind and replay handle to the switch lever to control the air tension to the lowest degree when the rewind and replay handle is shifted to rewind position.
